PNEUMATIC PLAY PEN

Shoji Suzuki, 6-11, 3-chome, Higashi-Mukojima,
Sumida-ku, Tokyo, Japan

Filed Apr. 6, 1972, Ser. No. 241,866

Claims priority, application Japan Oct. 20, 1971

Term of patent 14 years

Int. Cl. D6—06

U.S. Cl. D6—13

FIG.1

FIG.2

FIG.3

FIG. 1 is a top perspective view of a pneumatic play pen showing my new design with a bottom section thereof broken away to show the level of the floor of the pen; FIG. 2 is a top plan view thereof; and FIG. 3 is a bottom plan view thereof.

I claim:

The ornamental design for a pneumatic play pen, substantially as shown and described.
